Specification for Design.

Patented Sept. 6, 1910.

Application filed June 30, 1910. Serial No. 569,841. Term of patent 3½ years.

To all whom it may concern:

Be it known that I, SIDNEY O. BIGNEY, a citizen of the United States, residing at Attleboro, in the county of Bristol and State of Massachusetts, have invented a certain new, original, and ornamental Design for a Coin-Holder and Vinaigrette, of which the following is a specification.

In the accompanying drawings which form a part of this specification, Figure 1 is a front elevation of a coin holder and vinaigrette embodying my new design, and Fig. 2, a side elevation of the same.

I claim:

The ornamental design for a coin holder and vinaigrette, as shown.

SIDNEY O. BIGNEY.
